APPARATUS FOR ROLLING STRIP METAL

Richard G. Bennewitz, Jersey City, N. J., assignor
to Crucible Steel Company of America, New
York, N. Y., a corporation of New Jersey

Application August 3, 1940, Serial No. 350,789

3 Claims. (Cl. 80—32)

This invention relates to improvements in method and apparatus for cold drawing and rolling metal strip, bars and the like.

Apparatus for cold rolling metal strip has heretofore been devised, in which the strip is pulled between a pair of relatively small reducing or working rolls, each backed by an antifrictionally supported backing roll of much larger diameter, the axes of the four rolls all being in a common plane which is perpendicular to the direction of movement of the strip, this constituting the so-called "4-high" construction. This construction, however, is subject to a number of disadvantageous and undesirable features as follows. Owing to the fact that the working rolls are backed only in a direction perpendicular to the direction of rolling, but are unbacked or unsupported in the direction of rolling, they are subjected to lateral flexure or bending in this direction due to the pull exerted by the strip, such as is productive of a strip of non-uniform transverse thickness, and produces riffling at the edges. To minimize this tendency the working rolls must be made relatively large and the diameter of the backing rolls correspondingly increased to maintain their appropriate dimensions in relation to the working rolls. These large working rolls diminish the maximum reduction or "bite" that can be employed during rolling, while the combination of large working and backing rolls greatly increases the overall dimensions, weight and cost of the mill. Moreover, with the 4-high construction, although the backing rolls may be provided with antifriction bearings, such as roller bearings, this cannot be done with the working rolls due, for one reason, to lack of space and also, for the more important reason, that the working rolls must be set up tightly in split friction bearings, of babbitt or the like, to hold the working rolls rigidly in line as required with the backing rolls, and in order to make the requisite adjustments from time to time during rolling, to maintain the working rolls so aligned with the backing rolls. Antifriction bearings, such as roll or ball bearings, could not be employed for the working rolls in the 4-high construction, inasmuch as the "play" in the bearings thus introduced would cause misalignment of the working and backing rolls and thus produce riffling, buckling and non-uniform thickness of the strip. The fact that the working rolls must be thus tightly set-up in split friction bearings in the 4-high construction entails the further disadvantage that a steady flow of lubrication is required on the roll necks in order

to prevent over-heating of the bearings and roll necks. Owing to this heated oil splashing on the strip, it is impossible to produce a strip having a bright lustrous finish.

It is also known to construct cold rolling mills with a pair of working rolls each of which is backed by a pair of spaced backing rolls having their axes in a plane parallel to the strip and each bearing against the associated working roll, the so-called "cluster" construction. In mills of this type which have been heretofore devised, however, the working rolls have been directly driven through drive shafts connected thereto through "wobblers" or the like. Owing to the drive thus applied directly to the working rolls, these rolls must be made relatively heavy to minimize the resulting tendency for lateral deflection thereof, and the backing rolls must be made correspondingly larger and heavier than would otherwise be required in order to preserve the proper relative sizes of the working and backing rolls. Also the working rolls must be made sufficiently large so that such driving connections can be made thereto. To further minimize this lateral deflection and displacement of the working rolls, they must again be tightly set up in split friction bearings, requiring heavy and continuous lubrication during operation to prevent over-heating, with the resulting disadvantages above noted for the 4-high construction. Likewise, with this type of mill, it is difficult to roll strip of uniform cross-sectional thickness with a high degree of rapidity and with no riffling or buckling of the strip, and for the same reasons explained in connection with the 4-high construction.

In accordance with applicant's invention, the cluster arrangement of the working and backing rolls is employed, i. e., each of a pair of working rolls is backed by a pair of spaced backing rolls bearing against the same, but with this important distinction over the previous types of cluster mill constructions, that the working rolls are not themselves driven, but are merely cradled between and backed by their associated backing rolls. The strip or bar being rolled, is propelled entirely by tension applied to the strip or bar, i. e., the material being rolled is pulled through the mill. Owing to the fact that each working roll is cradled between and backed by a pair of backing rolls, and thus automatically maintained in proper alignment thereby, and owing to the further fact that no drive is applied to the working rolls, no bearings, other than loose thrust bearings, are required for the working

rolls. The working rolls are thus supported exclusively by the backing rolls in rolling contact therewith. Accordingly, the working rolls are subject to no over-heating or frictional drag, such as is produced in prior constructions due to the friction bearings required. Also since, as stated, each working roll is cradled and automatically aligned between a pair of backing rolls in contrast to the vertical roll arrangement of the 4-high construction, and since the working rolls are not themselves directly driven, as in the case of the prior cluster mill constructions, the working rolls of applicant's construction are not subject to flexure in the direction of rolling, as is the case with prior constructions. The working rolls and their associated backing rolls may accordingly be made much smaller than in the prior types of "4-high" or "cluster" mills, thereby greatly reducing the overall dimensions, weight and cost of the mill for any given size of stock to be rolled. The smaller working rolls which can thus be employed permit of reducing the stock to the desired dimensions in fewer passes than previously, due to the increased "bite" that can be employed effectively. Rolling costs are thus reduced and a superior product obtained.

Further in accordance with applicant's construction, the backing rolls are mounted in anti-friction bearings, such as roller bearings. Owing to this fact and the fact that no bearings are required for the working rolls, the bearing losses for the entire mill are reduced to such a point that the strip or bar may be rolled exclusively by tension applied thereto, i. e., by pulling the strip or bar through the mill and without danger of rupturing the stock. The friction losses are in fact so small that the stock can be rapidly reduced at a relatively high rate of speed, for example as high as 1500 feet per minute.

Applicant's construction has the advantage over the prior 4-high and cluster mills, that it can be employed for drawing and rolling special shapes, such as the conversion of round bars into square, hexagon, etc., shaped rods, or the reduction in cross-sectional area of round, square, hexagon, etc., shaped bars while maintaining their contour unchanged. This is accomplished by the use of work rolls having appropriately shaped grooves therein, such as V notches, etc., or more preferably by the use of "built-up work rolls" consisting of hardened and ground washers of appropriate contour. The self-aligning feature of the work rolls makes it possible to use such built-up rolls since roll necks and bearings are not required. Also with applicant's construction, it is possible to roll special edges on flat strips, by attaching an edge roll table to each end of the roll head. With this edge-rolling operation, it is possible to produce round, square or beveled shapes with a cold rolled finish, both on the flat portion of the strip as well as on the edges. Such rolling operations could not be carried out on the known types of 4-high and cluster mills.

Various further and more specific objects, features and advantages of the invention will appear from the detailed description given below, taken in connection with the accompanying drawings forming a part of this specification and illustrating merely by way of example certain embodiments of the invention. The invention consists in such novel features, methods, arrangements and combinations of parts as are shown and described herein.

In the drawings:

Fig. 1 is a plan view; Fig. 2 a view in front elevation and Fig. 3 a view in side elevation of a preferred embodiment of the apparatus of the invention.

Fig. 4 is a view in side elevation illustrating a clutch mechanism for connecting one of the reversing reels of the apparatus of Fig. 1, to its associated driving motor.

Fig. 5 is a transverse sectional elevation through the reducing and backing rolls and appurtenant parts, illustrating the manner in which the reducing rolls are cradled between and supported by the backing rolls.

Fig. 6 is a section at line 6-6 of Fig. 5; Figs. 7 and 8 are sections at line 7-7 and 8-8 of Fig. 1; Fig. 9 a section at line 9-9 of Fig. 8; and Fig. 10 a section at line 10-10 of Fig. 5.

Fig. 11 is an enlarged fragmentary view in side elevation corresponding to Fig. 2, showing the reducing rolls and associated guides for guiding the strip therebetween, one of the guides being shown in partial section; while Figs. 12 and 13 are sections at lines 12-12 and 13-13 respectively of Fig. 11; and Fig. 14 is a section at line 14-14 of Fig. 1.

Referring now to the assembly views, Figs. 1, 2 and 3, the particular embodiment of the apparatus here shown may comprise generally a rolling mill head 20 through which the strip material as at 21, which is to be reduced, may be passed either continuously in one direction, or alternately in one direction and then in the other, as it is wound or unwound from reels 22, 23. These reels may be driven by electric motors as at 24, 25 connected through clutches as at 26, 27, and reduction gearing of suitable known type 28, 29 to the shafts 30, 31 carrying the reels 22, 23 respectively.

Suitable brakes 32, 33 of known construction, for example, hydraulic brakes operating on the Alden dynamometer principle, according to which a braking action is provided by hydrostatic pressure due to the continuous flow of water, oil, etc., through a restricted orifice, whereby frictionally produced heat is carried away by the continuous flow of the liquid as the braking pressure is applied, may be connected or mounted upon the shafts 30, 31. Thus, for example, when the motor 24 is connected through clutch 26, the strip will be pulled through the mill head from reel 23 onto reel 22. During this operation, the strip is placed under considerable tension of about one-third to one-half of the elastic limit, as a result of the pull exerted by motor 24 and the back tension applied by brake 33, thereby greatly facilitating the rapid reduction in thickness of the strip without necessity for frequent reannealing.

When the strip has been thus completely passed through the mill and wound up on reel 22, the operation is reversed, motor 25 being actuated through clutch 27 to drive the strip in the opposite direction, while back tension is applied by brake 32. In this way, the thickness of the strip may be rapidly reduced to desired gauge in successive passes.

The mill-head 20 includes a main frame or housing 34 (Figs. 2 and 3) mounted upon a pedestal 35. Within main frame 34, the working and backing rolls are assembled and mounted in the manner shown more particularly in Figs. 5 to 10 inc., referred to in detail hereinafter, it being sufficient at this point to merely indicate the

general assembly, as shown in Fig. 5, according to which each of the working rolls 42, 43 is backed by a pair of backing rolls 60, 61 or 62, 63.

The backing rolls which are positioned above the strip may be supported in bearing housings 36, 36' (Figs. 2, 7, 8), similar bearing housings 37, 37' being provided for the backing rolls positioned below the strip. The housings 37, 37' may rest upon or be secured to the base of the outer housing 34 and retained against endwise movement therein, as by locking plates 38. The bearing housings 36, 36' may be similarly mounted within the housing frame 34 and retained by plates 39 against endwise displacement. However, the bearing housings 36, 36' are so mounted as to be slidably adjustable vertically so as to be able to adjust the size of the "pass" for the strip between the reducing rolls. Such vertical adjustment may be accomplished as by the use of two cooperating pairs of wedge blocks 40, 41 and 40', 41', hereinafter described in further detail.

In Fig. 2 the ends of two cooperating reducing rolls may be seen at 42, 43, the detailed construction of which will hereinafter be explained in connection with Fig. 10. Means for guiding the strip to and from the reducing rolls may also be seen at 44, 45, and the novel features thereof will be hereinafter described in connection with Figs. 5, 11, 12 and 13. Thumb nuts for adjusting same appear in Fig. 2 at 46, 47.

As shown in Figs. 1-3, the strip 21 in its travel to and from the mill head at each side thereof, may pass over water-cooled drums 48, 49, suitably journaled at the opposite ends of the pedestal 35 and provided with water inlet and outlet connections 50, 51. Also as indicated in Figs. 1 and 2, the strip may be passed through suitable wipers as at 52, 53, the same being shown in further detail in Fig. 14. For example, each wiper assembly may comprise a pair of felt pads 54, 55, engaging the upper and lower surfaces of the strip 21, the lower pad being supported upon a base member 56 and the upper pad upon a bar 57. The pressure of the pads upon the strip may be adjusted as by a hand wheel 58 acting upon the bar 57 against the pressure of springs 59 in a manner which will be apparent from Fig. 14.

The relative positions of the reducing rolls and backing rolls in respect to the path of travel of the strip 21 will be apparent from Fig. 5. The small reducing roll 42 is here shown as accompanied by two backing rolls 60, 61 of larger diameter and so placed as to form a cradle-like support for the reducing roll. Upper backing rolls 62, 63 similarly provide a cradle-like backing for the small upper reducing roll 43. Thus each reducing roll under the pressure of its engagement with the strip 21 has its alignment maintained and determined by the tangential contacts with two backing rolls so positioned angularly about the reducing roll that the latter is maintained against flexing or bending and the alignment of its axis is maintained against forces directed longitudinally of the strip as well as perpendicularly thereto. These conditions are maintained the same regardless of which direction the strip is pulled through the machine.

On each reducing roll the engagement with the strip and the contacts with the two backing rolls, provide an extended support for the reducing roll along three lines located at the vertices of a triangle, thus affording in effect a three-point support of each axial section of the reduc-

ing roll without requiring the use of any bearings on the latter. In this way the reducing roll is constantly self-aligning and positively supported in a single predetermined position and prevented from bending despite the powerful and variable pulling forces lengthwise of the strip, and despite severe and variable vertical pressures due to the engagement of the reducing rolls with the strip.

Hence, the reducing rolls, with a negligible amount of flexing, may be made of a very substantially smaller diameter than has been practicable heretofore in the "4-high" type of mill construction. And with such smaller reducing rolls a deeper "bite" may be taken in the strip being rolled, with less pulling power on the strip and consequently with lower operating expense and with no danger of tearing the strip. The action of the smaller roll on the strip is also such that greater reductions of the strip may be accomplished following each annealing of the strip and before it has to be again annealed for further reductions.

In the "4-high" type of rolling mill it is necessary to provide the reducing rolls with friction type split bearings to retain the rolls against displacement in the direction of movement of the strip being rolled, since the backing roll merely contacts with the reducing roll at a position diametrically opposite from the engagement with the strip. The use of such friction bearings involves a number of serious difficulties. For example, such bearings will at least in a large measure determine the alignment of the reducing roll independently of the backing roll, with the result that the contact pressure between the two rolls will vary from point to point and vary at different times depending upon the forces applied from engagement with the strip and the inaccuracies in bearing alignment. Thus, to avoid prohibitive misalignment, flexures of the reducing roll, and defects in the rolled strip, all of the rolls as well as the anti-friction bearings for the backing rolls, must be large, heavy and space-consuming. And it is necessary to make frequent adjustments of such split bearings, sometimes during operation of the machine, to maintain the reducing roll in proper alignment. On the other hand, with the construction of this invention, each of the reducing rolls is cradled by two backing rolls and thus being self-aligned, may be left free of any bearings (except for small thrust bearings to prevent endwise displacement, as hereinafter described). Thus the difficulties of the friction type split bearings required in 4-high mills are eliminated.

In the 4-high type of mill the friction type reducing roll bearings must tightly engage the roll necks to prevent play and consequent riffling and buckling of the strip. Anti-friction roller or ball bearings could not be used because of play afforded, particularly in directions lengthwise of the moving strip, and furthermore, because with the adjacent large anti-friction bearings and bearing housings for the backing rolls, there is insufficient space for anti-friction bearings on the reducing roll. The use of such friction type bearings not only involves a large power loss, but also necessitates a continuous flow of oil over the split bearings and the roll necks. Thus a steady flow of lubricating oil from the roll necks extends over the working surfaces of the reducing rolls, with the result that a bright finish cannot be obtained on the rolled strip. On the other hand, with the elimi-

nation of the split friction type bearings according to the present invention, no lubrication at the working rolls except for a small quantity of light rolling oil, is necessary, and this makes it possible to obtain a bright lustrous finish on the rolled strips.

With the arrangement of rolls as appears in Fig. 5, the flexing of the working rolls can be held down to a negligible amount by backing rolls having in the neighborhood of one-third the diameter of the backing roll of the old type "4-high" mill, even with working rolls of considerably smaller diameter. This may be accounted for by the cradle-like support afforded by the two backing rolls and the avoidance of the relatively long reducing roll necks heretofore necessary for bearing purposes, but having upon flexure against the bearings, such bending forces upon the rolls as to require larger rolls.

The reductions in size of the working and backing rolls as well as the triangular arrangement of each group thereof, makes possible a much more compact machine both as to height and width. I have found in practice that such a machine is capable of accomplishing the same work as a typical "4-high" mill of the old type, but at a faster rate with strip speeds up to 1500 feet per minute for the cold reduction of high carbon and alloy shapes and flats. For a 6" strip mill, for example, over half of the weight, and over 80% of the cost may be avoided in the construction of such a mill as compared with a typical mill of the "4-high" construction. And due to the accurate self-aligning of the reducing rolls, the use of small rolls and the improved "bite" of the reducing rolls, a 6" strip mill such as illustrated in the drawings may be operated for example by 75 H. P. as contrasted with 200 H. P. required for a corresponding "4-high" mill of the old construction.

The details of the arrangement of the reducing rolls and of the bearings for backing roll 61 are shown in Fig. 10. It will be understood that the other backing rolls, 60, 62 and 63 may be similarly mounted. As here shown, each end of the backing roll 61 may be supported in a large anti-friction bearing of the self-aligning roller type, including inner bearing races as at 64 embracing backing roll necks 65, and outer bearing races as at 66 secured in outer bearing rings as at 67. These bearing rings may be secured within the bearing housings 37, 37' against turning, as by pins 68. The roller bearings are shown as at 69 between the inner and outer bearing races. Packing rings formed, for example, of a suitable artificial rubber composition, are shown at 70 interposed between the bearing housings and shoulders as at 71 formed at each end of the backing roll.

Each end of each of the backing rolls may also be provided with an anti-friction roller type thrust bearing having inner and outer race rings as at 72, 73 with the roller bearings as at 74 therebetween. Each of the rings 73 may engage a backing ring as at 75, the latter in turn being received in cup-like casing members as at 76 adapted to be engaged by adjusting screws 77 mounted in the housing members 37, 37' and affording means for giving the backing roll its proper endwise adjustment. Lubrication for the backing roll bearings may be provided as through oil inlet and outlet pipes 78, 79 communicating with cavities and spaces in and around the bearings in a manner apparent in Fig. 10. The sup-

ports for the thrust bearings may be retained against turning as by pins 80.

As above indicated, the reducing rolls are left free for self-alignment by contact with the backing rolls and the work, and therefore need merely to be provided with small thrust bearings to retain the reducing rolls in proper adjustment endwise. Such thrust bearings are shown in Fig. 10 at 81 mounted in bearing housings as at 82 and 10 provided with sealing rings 83 of artificial rubber or equivalent material. The bearing housings 82 are free to assume positions vertically as determined by contacts of the backing rolls with the reducing roll. The adjustment of these bearing housings in directions endwise of the roll may be effected as by thrust adjusting screws 85, provided with operating knobs 86 and locking knobs 87. The inner ends of the adjusting screws 85 have threaded engagement with thrust blocks 88, 20 which in turn abut and loosely embrace the sides of bearing housings 82 with sufficient play to permit the reducing roll alignment to be freely determined by the backing rolls (Fig. 6). The outer ends of the adjusting screws 85 may be of reduced diameter as shown to provide shoulders 89 for engaging thrust plates 90. The thrust blocks 88 and plates 90 may be mounted for slideable adjustment, for example, in grooves or channels 84 formed in the upper surfaces of bearing 25 housing members 37, 37'. The plates 90 may be slid into place along the channels 84 and then held against outward movement by thrust latch members as at 91 (Fig. 10 and middle of Fig. 11). The members 91 may comprise a collar portion 30 for surrounding one of the screw members 85 and also two radially extending arms as appear in Fig. 11. The outer ends of these arms when the latch member is in position, are adapted to engage protruding portions as at 92, 93 formed on 40 the main bearing housing members at either side of the channel 84. But when the thrust assembly is being inserted along the channel, the latch member 91 may be turned as indicated by the dot and dash lines in Fig. 11 to a position permitting 45 one of its arms to enter as through a cut-out portion 94 of the bearing housing member. Turning of the latch member 91 may be limited as by pins 95, 96 mounted in thrust plate 90. The locking knobs 87 may bear against thrust collars 97 50 which in turn bear against and form bearings for latch members 91, whereby the parts between the locking knobs 87 and the shoulders 89 may be brought under pressure by the locking knobs to secure the screw members 85 against turning 55 after adjustments are made. It will be apparent that during the making of the thrust adjustments, by turning the screws 85 the thrust blocks 88 may be forced toward the end of the reducing roll through pressure applied to the screw members 85 by the latch members 91 acting through 60 the thrust plates 90 on the shoulders 89 of the screw members. The above described means for endwise adjustment of the lower reducing roll 42 may be in general substantially duplicated for 65 the upper reducing roll 43, as will be seen from Fig. 8.

The details of the mechanism for supporting and adjusting vertically the position of the upper bearing housings 36, 36' will now be described 70 with particular reference to Figs. 5, 7, 8 and 9. The lower wedge blocks 40, 40' may be secured to the upper sides of these bearing housings as by bolts 100. The wedge blocks 40, 40' in turn may be supported from the top of the outer housings 75 or frame 34, as by spring devices 101. Each

of these devices may comprise a cylinder 102 enclosing a heavy helical spring 103, the lower end of which bears against the lower closed end of the cylinder, and the upper end being connected to a suitable turnbuckle member as at 104 having an eyelet and pin or rod attachment 105 to the wedge block 40 or 40' (Fig. 5). This attachment (Fig. 7) may be made as by a rod 106 having ball shaped ends extending respectively into suitable apertures in the wedge members 40, 40'. The upper end of the spring cylinder 102 may be adjustably secured to the top of the main frame 34 as by a suitably threaded member 107.

As thus far described, it will be apparent that the bearing housings 36, 36' and wedge blocks 15 40, 40', and consequently also the rolls 62 and 63, are all so supported by the springs 103 as to be pulled upwardly to increase the gap or pass between the reducing rolls 42, 43. On the other hand, the wedge blocks 41, 41' are so shaped as to limit this upward movement to an extent depending upon the endwise adjustment of the wedge blocks 41, 41'. Such adjustment may be effected by lead screws as at 108 extending horizontally through wedge blocks 41, 41' in threaded engagement therewith, and mounted at their ends in suitable bearings in the sides of the main frame or housing 34. The screw rods 108 may be turned by large gear wheels as at 109 (Fig. 9), which in turn may engage a pinion 110 (Fig. 2). The pinion 110 may be operated as by a hand wheel 111, or automatically by a motor 112 connected through reduction gearing 113, pinions 114 and a suitable clutch 115. Thus, either by manual operation of the wheel 111 or by means of the motor 112, the upper reducing roll and its back- 30 ing rolls and the supporting structure therefor may be quickly and conveniently adjusted vertically as required, to provide the proper pass for the strip being rolled.

Means for guiding the strip to and from the working rolls will now be described. In each guide assembly the upper and lower surfaces of the moving strip may be engaged between a pair of relatively long wooden blocks as at 116, 117 formed of hard wood such as maple and having faces of suitable width and shape to engage the particular strip being rolled (Figs. 12, 13). The lower block may be carried by a supporting plate as at 118, which in turn may be carried by a plurality of supporting pins as at 119 extending down through the bearing housing members 37, 37' (Figs. 11, 5, 7), and adjustable vertically by small cam members 120 mounted upon horizontal rods as at 121. The upper wooden guide members 117 45 may be supported by and pressed down upon the surface of the strip being rolled as by clamping members 122 attached as by screws 123. The vertical positions of the clamping members 122 50 may be yieldably and adjustably retained by devices as shown in Fig. 5, including bell crank members 124 pivoted on the main frame as by rods 125, and having outer arms pivotally connected to pins as at 126, the upper ends of which pins are provided with adjustable thumb nuts as at 46, 47, acting against supporting brackets as at 127. Springs as at 128 may be interposed on the pins 126 between said brackets and the members 124.

The above described wooden guides and the supports therefor thus provide an effective means for straightening and properly guiding the strip to be rolled to and from the working rolls in such manner that buckling and bending of the strip are avoided. And the supports for the 70 75

guide blocks are so arranged that the elevation thereof may be conveniently adjusted if desired by turning the rods 121 and cams 120 after the mill has been started in operation. Furthermore, the support for the upper guide block is sufficiently yieldable to allow for these adjustments of the lower guide and by means of the thumb screws 46, 47, the pressure of the guide blocks on the strip may be readily adjusted during operation of the mill.

For guiding the strip edges a plurality of rollers as at 130, preferably having anti-friction bearings, may be mounted along each side of the strip adjacent the guide blocks 116, 117 (Figs. 6, 12, 13). These rollers may be mounted in supports as at 131, 132 carried by the supporting plate 118. The position of the supports 131, 132 relative to the edges of the strip, may be adjusted in the horizontal direction as by a lead screw 133 having oppositely threaded portions in threaded engagement respectively with the members 131, 132, as appears in Fig. 12. This lead screw 133 also serves to attach or secure the members 131, 132 in respect to the plate 118. The ends of the screw member 133 respectively may be mounted by suitable bearing means as at 134, 135 respectively, permitting the screw to be turned by a thumb screw 136, but preventing its displacement endwise. A locking thumb screw 137 may also be provided to act in a manner apparent from Fig. 12. Thus, by merely turning the knob 138, the positions of each group of guide rollers 130 at each side of the strip may be simultaneously adjusted to move the two groups of rollers an equal amount in opposite directions, thus insuring the maintenance of accurate centering of the strip despite adjustments of the pressure of the rollers against each edge or side of the strip. This affords an important advantage, permitting the guide rollers to be conveniently and properly adjusted from time to time during the operation of the rolling mill, as may be required. Plates 118 and the supporting members 131, 132 may be formed at their opposed faces with a cooperating tongue and groove construction as shown at 138, for guiding members 131, 132 during adjustment without jamming. Other tongue and groove constructions for like purposes may also be provided at each side of the screw 133 as shown at 139, 140 in Fig. 11.

The mill head as above described may if desired be used in conjunction with edge roll tables at both ends of the mill, making it possible to roll strips of round or square cross sections or with beveled edges. Also if desired, the above described rolling head may be attached to a so-called draw bench or draw block when it is desired to roll special shapes. In this event suitable grooves may be ground in the working rolls or the working rolls may be built up from a plurality of suitably shaped collars mounted upon a working roll arbor.

While the invention has been described in detail with respect to particular preferred examples, it will be understood by those skilled in the art after understanding the invention that various changes and modifications may be made without departing from the spirit and scope of the invention, and it is intended therefore in the appended claims to cover all such changes and modifications.

What is claimed as new and desired to be secured by Letters Patent is:

1. Apparatus of the class described for the cold

rolling of metal strip, said apparatus including a pair of work engaging rolls of relatively small diameter, each of said rolls being cradled between and in peripheral rolling engagement with a pair of backing rolls of larger diameter, said work engaging rolls being substantially free of radial bearing guidance except as provided by said backing rolls, anti-friction bearings supporting each of said backing rolls, said work-engaging and backing rolls being idle rolls, and devices for applying tension to the strip to pull the same between said work engaging rolls and rotate all of said rolls.

2. Apparatus of the class described for the cold rolling of metal strip, said apparatus including a pair of work engaging rolls of relatively small diameter, a pair of backing rolls of larger diameter for each of said work rolls, anti-friction bearings supporting the end portions of said backing rolls, said work rolls respectively being cradled between and in peripheral engagement with their respective backing rolls at points between the aforesaid bearings, said work engaging rolls being substantially free of radial bearing guidance except as provided by said backing rolls, said

work engaging and backing rolls being idle rolls, and devices for applying tension to the strip to pull the same between said work engaging rolls and rotate all of said rolls.

3. Apparatus of the class described for the cold rolling of metal strip, said apparatus including a pair of work engaging rolls of relatively small diameter, each of said rolls being cradled between and in peripheral rolling engagement with a pair of backing rolls of larger diameter, said work engaging rolls being substantially free of radial bearing guidance except as provided by said backing rolls, anti-friction bearings supporting each of said backing rolls, said work-engaging and backing rolls being idle rolls, said work engaging rolls having thrust bearings engaging the end portions thereof which are constructed and arranged to suppress endwise movements thereof, but to afford relative movement of one of said work engaging rolls toward and from the other, and devices for applying tension to the strip to pull the same between said work engaging rolls and rotate all of the aforesaid rolls.

RICHARD G. BENNEWITZ.
